By his Attorneys,

C. Brown & Co.

UNITED STATES PATENT OFFICE.

THEODORE L. BAUMGARTEN, OF HORNELLSVILLE, NEW YORK, ASSIGNOR
OF ONE-HALF TO FARRAND C. PRINDLE, OF SAME PLACE.

SLIP-SHAFT COUPLING.

SPECIFICATION forming part of Letters Patent No. 517,787, dated April 3, 1894.

Application filed March 18, 1893. Serial No. 466,705. (No model.)

To all whom it may concern:

Be it known that I, THEODORE L. BAUMGARTEN, a citizen of the United States, residing at Hornellsville, in the county of Steuben 5 and State of New York, have invented a new and useful Slip-Shaft Coupling, of which the following is a specification.

This invention relates to slip shaft couplings; and it has for its object to provide an 10 improved shaft coupling that is designed to firmly couple adjacent shaft ends together, while at the same time providing a coupling especially adapted for coupling the shaft of grinding and crushing machinery to a round 15 drive shaft, so that when hard foreign substances work their way into the machinery, the same will not be injured owing to the construction of the coupling which allows the drive shaft to slip therein, thereby stopping 20 the machinery being driven.

With these and many other objects in view which will readily appear as the nature of the invention is better understood, the same consists in the novel construction, combination, 25 and arrangement of parts hereinafter more fully described, illustrated, and claimed.

In the accompanying drawings:—Figure 1 is a perspective view of a shaft coupling constructed in accordance with this invention, 30 Fig. 2 is an end view thereof. Fig. 3 is a central vertical longitudinal sectional view on the line X—X of Fig. 2. Fig. 4 is a longitudinal sectional view on the line Y—Y of Fig. 2.

Referring to the accompanying drawings, 35 A represents a cylindrical coupling block or casting having a square bore B, at one end adapted to fit over the squared end C, of a mill or other machinery shaft, while the other end of the block is provided with a circular bore D, into which is designed to fit one end of the circular ungrooved drive shaft E, exteriorly and slightly flattened at one side as at F, for the purpose hereinafter described.

The circularly bored end of the coupling block or casting A, is exteriorly tapered as at 40 G, and is provided in such end with the slits H, and the key seat or groove I, formed in the bore between said slits, and adapted to receive the elongated flat key J, which is of a 45 width equaling the depth of the groove and

ordinarily bears flat against or in contact with the exteriorly flattened side of the drive shaft E, so as to prevent the same from turning in the coupling in ordinary work.

The tapered end of the block or casting A, 55 is adapted to receive the interiorly beveled clamping collar or ring K, which is provided with opposite notched ears L, adapted to receive the shouldered ends M, of the coupling screws N. The shouldered ends of the coupling screws or bolts N, are formed by annular grooves which fit in the notched ears of the coupling ring or collar, and the threads of said screws engage the integral threaded lugs O, projecting laterally from opposite sides of 60 the coupling block or casting A. Having fitted the two ends of the shafts C and E, into the coupling block A, as described, it is only necessary to manipulate the coupling screws N, so as to compress the split end of the coupling block onto the shaft and wedge it in position sufficiently tight against one side of the key J, so as to prevent it from turning in ordinary work. When hard foreign substances interfere with the machinery driven 65 by the shaft G, the coupling necessarily stops 70

short with a jerk, which jerk is sufficient to allow the exteriorly flattened side of the drive shaft E, to slip past the flat key J, and therefore allows such shaft to turn or slip in the 75 coupling, thereby relieving the machinery being driven, from all strain and danger of breaking. The slit end of the coupling block and the coupling ring yield sufficiently in order to allow the drive shaft to turn in the 80 coupling without breaking the same. The coupling ring or collar necessarily stretches slightly after each time the drive shaft has forced itself around in the block, and this stretch is compensated for by the taper of the 85 block A, on which the ring is fitted each time.

From the foregoing it is thought that the construction, operation and many advantages of the herein-described slip shaft coupling will be apparent without further description. 90

Having thus described my invention, what I claim, and desire to secure by Letters Patent, is—

1. In a slip shaft coupling, the combination of a cylindrical coupling block provided at 95

one end with a circular bore and a squared key-seat or groove formed in one side of said bore, a flat key of a width equaling the depth of said key seat or groove and fitting therein, 5 the round shaft-end fitted in said circular bore and having an exteriorly-flattened un-grooved side bearing flat against the inner flat face of the key, and means for compressing the bored end of the coupling block, substantially as specified.

2. In a slip shaft coupling, a coupling block having a square bore at one end, off-standing threaded lugs, and an opposite exteriorly tapered end provided with a cylindrical bore, 15 and having slits formed therein and a key seat or groove, a square key adapted to be inserted in said key seat or groove and to fit

the flattened side of a round shaft end, an interiorly beveled clamping collar or ring fitting the exteriorly tapered end of the block 20 and provided with opposite notched ears, and shouldered coupling screws or bolts removably fitting the notched ears of the collar or ring and adjustably engaging the threaded lugs of the coupling block, substantially as 25 set forth.

In testimony that I claim the foregoing as my own I have hereto affixed my signature in the presence of two witnesses.

THEODORE L. BAUMGARTEN.
